Columbian Enameling & Stamping Co., Inc.,
Terre Haute, Ind., a corporation of Indiana

Application June 28, 1937, Serial No. 70,082

Term of patent 3½ years

To all whom it may concern:

Be it known that I, Andrew W. Nelson, a citizen of the United States, residing at Terre Haute, in the county of Vigo and State of Indiana, have invented a new, original, and ornamental Design for a Basket Cooker, of which the following is a specification, reference being had to the accompanying drawing, forming part thereof.

Fig. 1 is a top plan view of the basket cooker,
showing my new design;

Fig. 2 is a view in side elevation of the basket
cooker; and

Fig. 3 is a bottom view of the basket cooker.

I claim:

The ornamental design for a basket cooker, as shown.

ANDREW W. NELSON.
